(57) **CLAIM**

The ornamental design for a fingerprint reader for authentication device, as shown and described.

DESCRIPTION

FIG. 1 is a perspective view of a fingerprint reader for authentication device showing our new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings illustrate environment and portions of the fingerprint reader for authentication device that form no part of the claimed design. The dash-dot-dash broken lines in the drawings define the boundaries of the claim, and form no part thereof.
